atty.

UNITED STATES PATENT OFFICE.

SAMUEL FREUND, OF CHICAGO, ILLINOIS.

FOLDING BOX.

1,383,714.

Specification of Letters Patent.

Patented July 5, 1921.

Application filed December 12, 1919. Serial No. 344,382.

To all whom it may concern:

Be it known that I, SAMUEL FREUND, a citizen of the United States, and a resident of Chicago, in the county of Cook and State 5 of Illinois, have invented new and useful Improvements in Folding Boxes, of which the following is a specification.

My invention relates to paper boxes and particularly to that class in which the container member and the cover member are each formed from a single piece of paper, fiber, or other suitable material bent to form the sides and ends, together with means for interlocking such sides and ends at the corners. As at present constructed lock corner boxes have the tendency to break in the corners, the locking tongue sliding out of the receiving slot or breaking off in the box after insertion. An important object of my 20 invention is therefore to overcome the weaknesses in prior boxes by improved corner locking mechanism.

Another object of the invention is to provide such arrangement and shape of tongue 25 and slot construction that the locking tongues will under pressure automatically guide themselves into the slot and will thereafter form strong interlocking engagement with the material surrounding the slot.

Another object of the invention is to provide such construction and arrangement that the box will be heavily reinforced at the corners where strength is mostly necessary.

The above and other features of my invention are clearly disclosed on the accompanying drawing in which

Figure 1 is an end elevational view of the box cover showing one corner partly open,

Fig. 2 is an end elevational view of the 40 container member with one end in vertical section to show the interlocking engagement at the corner,

Fig. 3 is a plan view of the formed blank of paper from which the cover member is 45 folded up, and

Fig. 4 is a plan view of the paper blank from which the body or container member is folded up.

The cover member and container member 50 are each formed from a single piece of paper or other suitable material. A rectangular piece of paper for the cover member is creased longitudinally near its sides along the lines 5 and 6, and is creased or scored 55 transversely near its ends along the lines 7 and 8. The score lines divide the blanks

into the rectangular body part 9, the sides 10 and 11 and the ends 12 and 13. These ends are cut along lines which are coincident with the longitudinal scoring lines 5 and 6, 60 such cutting being indicated by the reference character 14, the cutting extending as far as the transverse score lines 7 and 8 respectively. Cutting along the line 14 produces the corner sections or flaps 15 which 65 form continuations of the sides 10 and 11 and are hinged at the score lines 7 and 8 respectively. Extending from substantially the center of the hinge line of each corner and diagonally toward the outer point of 70 such corner is a slot 16, the laterally extending slot section 16' forming a continuation of the slot 16, the two forming a more or less L shaped slot which surrounds a tongue 17.

Each of the sides 12 and 13 is cut transversely a distance inwardly from each corner thereof, the cut being represented by the character 18. The outer end of the paper section between the cut and the adjacent edge of the sides is cut away to leave 80 a short tongue or stub 19, cutting being on the bias so as to leave the inclined end edge 20 on each tongue or stub. The cuts 18 are more in the nature of slots, that is they have width. 85

The arrangement for the container member shown in Fig. 4 is the same as that for the cover member of Fig. 3 except that the location of the cuttings is different. Instead of cutting the ends 12 and 13 as at 14, the 90 sides 10 and 11 are cut in coincidence with the folding lines 7 and 8 as indicated by the reference character 21, this leaving the corners or flaps 22 hinged to the ends 12 and 13 instead of to the sides. The slots 95 23, 23' in the corners extend from the folding lines 5 and 6 respectively, and the tongues 24 corresponding to the tongues 19 of the cover member are formed at the ends of the sides 10 and 11. 100

To form the cover member the blank of Fig. 3 is folded along the lines 5, 6, 7 and 8 into position at right angles with the body section 9. The corners 15 which were also folded along the lines 7 and 8 are placed 105 on the inside. The tongues 17 are then deflected outwardly a distance so that the stubs 19 may readily enter the slots 16, 16'. These stubs enter the slots at their heels 19' and the inclined edge 20 engages with the end 110 e of the slot 16' and the stub 19 is automatically forced into position to drop through

the slot as the sides and ends of the container part are brought together into positions at right angles with each other. As soon as the point of a stub leaves the end 5 of a corresponding slot the stub drops through the slot, the tongues 17 and the stubs 19 at the various corners being then in interlocking engagement which can only be broken by forcible relative movement of the 10 sides and ends in directions at right angles with the body section 9.

To form the other member of the box the blank shown in Fig. 4 is folded along the lines 5, 6, 7 and 8 and the corners 22 are 15 arranged against the inside of the side walls 10 and 11. During shifting of the corners into such position the stubs 24 pass through the slots 23, 23', the tongues and stubs being finally brought into interlocking engage- 20 ment.

As the corners 15 of the container part are held against the ends 12 and 13, and the corners 22 of the cover part are held against the sides 10 and 11, the box structure is 25 heavily reinforced at its corners where the greatest strength and rigidity is required. The stubs 19 and 24 being short and the tongues 17 being likewise short, and these members being held together in interlocking 30 engagement after folding, the stubs and tongues cannot readily break off and their disengagement is prevented except by relative movement between the corners and box sides in a direction at right angles to the 35 body sections of the members. I thus produce a very strong and reliable box having maximum capacity for the amount of paper used for its construction. My improved interlocking arrangement is applicable on dif- 40 ferent styles of boxes.

I claim as follows:—

1. In a foldable paper box, side and end walls, corner sections hinged at the ends of said walls, a slot in each corner section and 45 a tongue surrounded by such slot, and a stub formed along the edge of the adjacent side of the box for engaging in said slot, said stub having an inclined edge for facilitating its passage into said slot, said tongue and 50 stub interlocking after passage of the stub through said slot.

2. A paper box member folded longitudinally and transversely near its edges to form sides, one set of sides being cut in line coincident with the folding line for the other side to leave corner sections, said corner sections having each an L shaped slot, the side sections between said corner sections having sections cut away to leave stubs formed 55 along the edge of the section, said stubs extending through said slots to have interlocking engagement with the corner sections.

3. A paper box member formed from a rectangular sheet of paper folded trans- 60 versely and longitudinally near its ends to

form end and side sections, the end sections being cut across coincident with the folding line for the side sections, whereby the ends are divided into central sections and corner sections, said corner sections having slots extending outwardly from their folding lines, and stubs formed along the edge of the sides of the end center sections for extending through said slots and interlockingly engaging with the corner sections when the paper 75 blank is folded.

4. A paper box member formed by folding a rectangular paper blank longitudinally and transversely to form side and end walls, the end walls being cut transversely in line coincident with the folding lines of the side walls whereby such end walls are converted into central sections and corner sections, each corner section having a slot extending diagonally from its base toward its outer point, 85 said center sections being cut away at their outer corners to leave stubs formed along the edge, said stubs passing through said slots for interlocking engagement with said corner sections when the paper blank is folded up. 90

5. A paper box member formed by folding a rectangular paper blank longitudinally and transversely to form side and end walls, the end walls being cut transversely in line coincident with the folding lines of the side 95 walls whereby such end walls are converted into central sections and corner sections, each corner section having a slot extending diagonally from its base toward its outer point, said center sections being cut away at their outer 100 corners to leave stubs, said stubs formed along the edge passing through said slots for interlocking engagement with said corner sections when the paper blank is folded up, the ends of said stubs being inclined where- 105 by to facilitate entrance of said stubs through said slots.

6. A blank for forming paper box members in the form of a rectangular sheet, longitudinal and transverse scoring lines near 110 the ends of said sheet for determining the end walls, said sheet at opposite ends being cut transversely coincidentally with the folding line whereby to divide each end section into a middle section and corner sections, the 115 corner sections having diagonal slots extending from their bases toward their outer point, and stubs formed along the edge at the outer corners of the adjacent center section for entering said slots and interlockingly en- 120 gaging with the corner sections.

7. A paper box member folded longitudinally and transversely near its edges to form sides, one set of sides being cut in line coincident with the folding line for the other 125 side to leave corner sections, said corner sections having each an L shaped slot, the side sections between said corner sections having sections cut away to leave stubs formed along the edge, said stubs extending through 130

said slots to have a rigid interlocking engagement with the corner sections.

8. A paper box member folded longitudinally and transversely near its edges to form 5 sides and a body section, one set of sides being cut in line coincident with the folding line for the other side to leave corner sections, said corner sections having each an L shaped slot, the side sections between said 10 corner sections having sections cut away to leave stubs formed along the edge, said stubs

extending through said slots to have a rigid interlocking engagement with the corner sections and adapted to be disengaged only by a relative movement between the corners 15 and box sides in a direction at right angles to the body section.

In witness whereof I hereunto subscribe my name this 9th day of December, A. D. 1919.

SAMUEL FREUND.
